DESIGN FOR A FLOWER POT

George A. Grau, Cincinnati, Ohio

Application May 18, 1942, Serial No. 106,942

Term of patent 14 years

To all whom it may concern:

Be it known that I, George A. Grau, a citizen of the United States, residing at Cincinnati, in the county of Hamilton and State of Ohio, have invented a new, original, and ornamental Design for a Flower Pot, of which the following is a specification, reference being had to the accompanying drawing, forming part thereof.

In the drawing:

Fig. 1 is a top plan view of a flower pot showing my new design.

Fig. 2 is a side elevational view of the flower pot.

Fig. 3 is a bottom plan view of the flower pot.

The characterizing features of the design reside in a flower pot having reflecting facets or panels on the outer surface thereof as shown.

I claim:

The ornamental design for a flower pot, substantially as shown and described.

GEORGE A. GRAU.
